UNITED STATES PATENT OFFICE.

JOHN F. THUNELL, OF SALT LAKE CITY, UTAH.

HAND-PLANE.

1,171,076.

Specification of Letters Patent. Patented Feb. 8, 1916.

Application filed November 17, 1914. Serial No. 872,608.

To all whom it may concern:

Be it known that I, JOHN F. THUNELL, a citizen of the United States, residing at Salt Lake City, in the county of Salt Lake 5 and State of Utah, have invented certain new and useful Improvements in Hand-Planes, of which the following is a specification.

This invention relates to bit adjustments 10 for hand planes, and the object of the invention is to provide novel and peculiar means for adjusting hand plane bits which shall be of simple construction, conveniently assembled, and accurately manipulated.

The object of the invention is to provide novel and peculiar means for adjusting and fixing the plane bit, and special means for hanging and adjusting the base or surface 20 bearing plates of the plane.

A further object of the invention is to provide in the bit adjustment, convenient, simple, durable and effective means for giving the bit minute, accurate and positive 25 adjustment independent of the base plate adjustment.

A still further object of the invention is to provide a pair of surface or runner plates, and a screw rod hinged to each 30 plate, and a pair of adjusting and locking nuts for each rod, the adjusting nuts being held within the plane stock.

Other objects, advantages and improved results will be found in the practical application of the plane.

In the accompanying drawings forming part of this application: Figure 1 is a side elevation showing in dotted lines the various positions of the base plates. Fig. 2 is a 40 sectional view of the bit device. Fig. 3 is a detail cross section on the dotted lines $x-x$, Fig. 2. Fig. 4 is a detail perspective view of the bit bracket.

The same reference characters denote the 45 same parts throughout the several views of the drawings.

The plane stock or body 1, has a concavity 2 in its top in which set-screws 3 and 4 are operated in connection with a bit 5 and its keeper 6. The screw 3 works through a 50 hinged carrier 1^a, to connect the keeper therewith, and the thumb screw 4 works through the upper end of the keeper as

usual. A transverse opening 7 is made through the stock under the concavity 2, 55 and a bit slot 2^a is made through the bottom wall of the opening 7. The under side of the stock is cut out at 8, for the purpose of reducing the weight of the plane, and for the purpose of housing the bit adjusting 60 device. The bit adjusting device comprises a bracket the long plate 9 of which has a lug 8^a working in the bit slots 9^a covered by the plate 9, and the short plate 10 of the bracket is secured to the inclined wall 11 65 of the cut out portion 8 of the stock. The plate 10 forms a collar 10^a in which a worm screw 12 is operated. Said screw having a stem extending through the top of the stock on an incline and parallel with the 70 bit, and the stem is provided with a thumb bit, and the stem is provided with a thumb head 13 for operating the screw. The plate 9 is provided with a follower projection 14 meshing with the screw 12, and the plate 9 has a forked end for the plate 10. 75

The pair of flexible runners 15, have their inner ends secured flush with the bit slot 2^a, and the outer end of each plate is curved upwardly. A screw rod 16 is hinged or pivoted at 17 adjacent to the said curved 80 end of each plate, and said rods extend through the ends of the stock 1. The ends of the stock are provided with transverse slots 18 and hold thumb nuts 19 for operating the rods 16, and set nuts 20 are provided for holding the rods in set position. One end of the stock is provided with a hand abutment 21 projecting above the nut 20 at this end of the stock, and thereby 85 prevents the hand from interfering with the nut and rod.

It will be observed that the follower answers two purposes, it forms the connection between the bit and the bracket, and it also affords means for imparting to the bit the 90 movement of the worm screw.

Having thus described my invention what I claim as new and desire to secure by Letters Patent is:—

In a bit plane, a plane throat the under 100 wall of which has a slot lengthwise thereof, a plate of larger area than the slot and slideable on the under face of said wall opposite the slot, a lug on the upper face of the plate and projecting through the slot 105 into engagement with the bit, a lug on the

lower face of the plate, and a screw spaced apart from said wall equal to the thickness of the plate and engaging the plate and the lower lug to keep the upper lug in engagement with the bit for longitudinal adjustment by the screw.

In witness whereof I hereunto set my hand in the presence of two witnesses.

JOHN F. THUNELL.
